UNITED STATES PATENT OFFICE.

GEORGES HENRI ROBICHON, OF THREE RIVERS, QUEBEC, CANADA.

INDEX.

1,278,019.

Specification of Letters Patent. Patented Sept. 3, 1918.

Application filed November 24, 1916. Serial No. 133,237.

To all whom it may concern:

Be it known that I, GEORGES HENRI ROBICHON, a subject of the King of Great Britain, residing at Three Rivers, Province 5 of Quebec, Canada, have invented certain new and useful Improvements in Indexes; and I do hereby declare that the following is a full, clear, and exact description of the invention, such as will enable others skilled 10 in the art to which it appertains to make and use the same.

The present invention relates to indexes and more particularly to a system of indexing various subjects or names which may 15 be used by offices, libraries and merchants whether having a small or large number of subjects or names to record. An object of the present invention is to provide indexes of the character aforesaid wherein a large 20 or a small number of names or subjects may be easily and readily classified and after once being classified within the indexes the names or subjects indexed will not commingled, but any particular name or subject may 25 be easily and readily found with the greatest celerity.

With the above and other objects in view the invention consists of an index book in which the respective pages or sheets are 30 divided up into spaces and each space may be alphabetically or numerically indicated wherein any number of names or subjects may be classified, as will be hereinafter more fully described.

35 In the drawings have been shown the preferred forms of the invention, it being, however, understood that no limitation is necessarily made to the precise structural details herein exhibited, but the right is hereby 40 reserved to any changes, alterations or modifications that come within the scope of the appended claims without departing from the spirit of the invention or sacrificing the efficiency of the same.

45 In the accompanying drawings:

Figure 1 is a memorandum book illustrating one sheet thereof having the principle of the index system printed therein; and,

Fig. 2 is a slightly modified form.

50 The page as disclosed in Fig. 1 is ruled with horizontal and vertical lines forming a series of vertical columns each of which are numbered and the numbers run from one to thirty-one inclusive and at the extreme 55 right hand of the sheet there is provided a

blank column the purpose of which will be later disclosed. At the left hand side of the page there is ruled two vertical broad columns and one of the columns will provide room for keeping the pages within 60 the binder, whereas the other column is to include names or articles to be classified. At the top of the name column the date appears to indicate the time the page was started or if one prefers he may put a 65 number instead of the date or any other indication he may desire. In using this system a subject matter that should be attended to is given a title when received, which title is written on that subject matter and in the 70 name column; this title is stamped with the date of entry in the name column or with any other indication that appears at the top of the name column. Supposing that a lawyer is keeping this system and the name 75 column has been started on November 1st, 1916, he receives on November 3rd 1916 a claim or any other matter that should be attended to: first, he gives a title to this claim or matter; secondly, he writes it on 80 that subject matter and in the name column; thirdly, he puts on the subject matter the date he enters it in the name column or any other indication that appears at the top of the name column. Supposing now that this 85 matter requires attention on the day it is entered, a check mark is placed within the vertical column designated by the numeral corresponding with that day; if it requires attention only at a later date previous to the 90 same date of the next month, a check mark is then placed within the vertical column designated by the numeral corresponding with that later date; and if it requires attention at the same date of the next month 95 or any other date after, the check mark is placed within the blank column. The next claim to be entered is attended to in the same manner and so on and likewise the date when such needs attention should be 100 checked in the vertical column designated by the numeral or otherwise as explained above. Each day the keeper of this system runs down the vertical column which is designated by a numeral corresponding with 105 the date of that day and readily ascertains which matters require attention on that day. If the subject matter was attended to on the date checked and should be attended to again later the check mark should be erased 110

and another check mark should be placed within the vertical column corresponding with the date that it should be seen again, providing this date falls before the same 5 date of the following month, otherwise it should be checked in the blank column. If a subject matter that has been attended to on say November 4th 1916 is to be attended to again on the 9th day of November 1916, 10 the check mark in the vertical column designated by the numeral 4 is erased and another check mark placed within the vertical column corresponding with the date that it should be seen again; if on the contrary 15 the subject matter is to be attended to only on the 9th day of December 1916 the check mark is placed within the blank column, and at the end of November that check mark is erased from that blank column and 20 placed in the 9th column; and if the matter needs attention only on the 9th day of January instead of the 9th day of December, the check mark in the blank column is not erased until the end of December. At the 25 end of the month the keeper runs down the blank column to ascertain if any matter checked in that blank column should be attended to the following month and if so he erases the check in that blank column and 30 places it within the vertical column corresponding with the date that it should be seen to. Any check appearing on this vertical blank column indicates that the subject matter is still under consideration but has 35 been suspended indefinitely or for a later date that will not come up during the month. When any of the subject matters classified have been closed and terminated, an X mark or any other sign is placed in the first column indicated by the numeral 1 as under 40 the title of Linton *vs.* Bastien; in this manner the keeper may readily trace down the first column to ascertain which matters have been closed; any other means may be also 45 used. The matters are placed in the ordinary manner within a cabinet, so that they may be found without referring to this memorandum index. By providing the date at the top of the name column when each 50 column was started, the keeper may easily find the title to each subject matter when knowing on or about what date he received this subject matter; for instance, the page that was started on November 3rd 1916 was 55 completely filled with names by November 10th and page 2 commenced with the date of November 11th 1916, and should Mr. Brown come within the office of the keeper at some later date and state that a subject matter 60 was given to the keeper in the first part of November 1916 without being able to give any other information; to locate this matter the keeper should refer to the page of the memorandum index system containing 65 the date given by Mr. Brown and by glanc-

ing down the name column he can readily locate the subject matter in which Mr. Brown is interested, noting at once when the same needs attention or whether the same has been closed.

The modification of this system as disclosed in Fig. 2 is substantially the same and works on substantially the same manner, but instead of providing a single vertical blank column at the right hand side of the 70 sheet for containing marks indicating that the subject matters on that sheet are to be attended to at a future date, I provide on this system twelve additional columns and each column being designated by the month 75 of the year. In using this system supposing that the Jones *vs.* Miller matter was received on November 1st 1916 and that the same is to be answered on November 4th 1916, a check mark is placed within the vertical column designated by the numeral 4, but should the Smith *vs.* Roe matter be received on November 1st 1916 and is not to be attended to until some day in January, a check mark will be placed in the column 80 of January.

In each of these figures additional sheets may be interposed or added.

Each page is shown as provided with a marginal tab having on each side a numeral. 95 There are fifty pages, for instance, in a book, and the odd numerals appearing on the one side of the tabs are ranged from 1 to 49, while the opposite faces of the tabs are provided with even numerals from 2 to 50. 10 When the book contains more than fifty pages, the numerals would be correspondingly increased. At the top of the subject's column the numeral may appear which corresponds with the numeral of the tab of that 10 page, as seen in Figs. 1 and 2 above the date in the subject's column.

From the foregoing it is obvious that with an index diary or memorandum arranged in accordance with the principle of the system herein described, the names or subjects may be written very compactly so that space may be economized and that the matter contained therein may be found at a glance, so that but very little time will be lost in looking up 11 any names or subjects desired.

Having thus fully described my invention, what I claim as new and desire to secure by Letters Patent is:

1. An index comprising a sheet being 120 ruled to form horizontal rows and vertical columns, calendar designating marks for said vertical columns, a vertical title column for receiving subjects to be indexed arranged at one side of the sheet and parallel with 125 said vertical columns and said vertical columns to receive indicating marks for connecting the calendar marks with the subject matter indexed and a vertical column at the side of the sheet opposite said title column 130

for receiving check marks of an indicating character other than those in said vertical columns.

2. An index comprising a sheet being ruled with horizontal and vertical lines to form a vertical title column at one side of the sheet for receiving subjects to be indexed and a plurality of columns arranged at one side of the sheet and parallel with said title column, each of said vertical columns being designated by a numeral and said numerals corresponding with the days of the month, a plurality of vertical columns

for receiving check marks for indicating dates other than those in said vertical columns and said numerical designated columns and vertical blank column being for the reception of check marks whereby the subject matter contained in the title column will be designated by a day of the month substantially as and for the purpose specified.

In witness whereof I have hereunto set my hand.

GEORGES HENRI ROBICHON.
